HIS ATTORNEY

UNITED STATES PATENT OFFICE

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY

PNEUMATIC TOOL

Application filed March 3, 1928. Serial No. 258,840.

This invention relates to pneumatic tools, but more particularly to a sleeve adapted to be disposed about the cylinder of the tool to form an exhaust chamber into which the pressure fluid utilized for actuating the hammer piston may be exhausted.

The objects of the invention are to prevent the agitation of dust and dirt in the vicinity of the drilling operation and to prevent the entrance of such dust and dirt into the reciprocating element of the tool.

Other objects will be in part obvious and in part pointed out hereinafter.

In the accompanying drawings forming part of the specification and in which similar reference characters refer to similar parts,

Figure 1 is a sectional elevation of a pneumatic tool constructed in accordance with the practice of the invention, and

Figure 2 is a perspective view of the sleeve.

Referring more particularly to the drawings, the invention is shown applied to a pneumatic tool having a cylinder A in which is disposed a hammer piston B for delivering blows of impact to a working implement C. The working implement C in this instance projects with its rearward end into the front end of the cylinder and is guided by a bushing D disposed in the front end of the cylinder A to form a closure therefor. A free exhaust port E or, as illustrated, a series of such ports, are formed in the cylinder A intermediate its ends to convey the pressure fluid from both ends of the cylinder and are controlled only by the piston B.

On the rearward end of the cylinder A is threaded an extension or hood F which may be an integral portion of a handle (not shown) whereby the tool may be manipulated. A bore G of the hood F into which the rearward end of the cylinder A extends is preferably of sufficient depth to permit the insertion in the rearward end thereof of a valve plate H which forms a closure for the rearward end of the cylinder. The plate H has diverging surfaces J and K which serve as seats for a distributing valve L adapted to oscillate in a valve chamber O in the rearward end of the bore G.

Pressure fluid for actuating the tool may

be admitted into the valve chamber O through a passage P and the admission of such pressure fluid into the rearward and front ends of the cylinder A is effected through inlet passages Q and R respectively. 55

In accordance with the present invention, means are provided for diffusing the pressure fluid exhausted from the cylinder in order to prevent the direct flow of such exhaust to the atmosphere, with the resulting agitation of dust and dirt in the vicinity of the drilling operation. To this end a sleeve S is disposed about the tool to form an exhaust chamber T around the cylinder adjacent the exhaust ports E. The sleeve S is 60 split longitudinally from one end to the other as at U to provide an escape for the pressure fluid from the chamber T and to diffuse such pressure fluid during its passage from the chamber to the atmosphere. In this way the 70 exhaust fluid may escape along the entire length of the split portion of the sleeve instead of being exhausted directly to the atmosphere from the cylinder in a solid stream.

The sleeve S engages a cylindrical surface V on the cylinder A and may abut with its front end a shoulder W adjacent the surface V for preventing endwise movement of the sleeve S in a forwardly direction. Similarly, the rearward end of the sleeve S which 75 is of larger diameter than the forward end engages surface X on the hood F, said surface F accordingly also being larger than the surface V and at the rearward end of said cylindrical surface is a shoulder Y which acts 80 as an abutment for preventing movement of the sleeve S in a rearwardly direction.

To assure the ready assembly of the sleeve S in the operative position, the diameter of the cylinder A through the surface V may be 85 at least equal to the diameter of the cylinder at any point between the surface V and the rearward end of the cylinder, and likewise the diameter of the hood F through the surface may be at least equal to the diameter of the hood at any point between the surface X 95 and the front end of the hood.

In order to insure against unauthorized rotative movement of the sleeve S with respect to the element which it engages, the 100

ends of the sleeve are formed of slightly smaller diameters than those of the cylindrical surfaces V and X. By so doing it is necessary to distend the sleeve somewhat when placing it in its assembled position in order to enable the ends of the sleeve to be disposed on the cylindrical surfaces. In this way a tension will be set up in the sleeve and such tension will be sufficient to maintain the sleeve firmly on the cylindrical surfaces V and X in any position in which it may be placed on the cylinder.

I claim:

In a pneumatic tool, the combination of a cylinder having a free exhaust port, a hood threaded on the rear end of the cylinder, a cylindrical surface on the hood of a diameter at least equal to the diameter of the hood at any point between said surface and the forward end of the hood, a cylindrical surface on the cylinder of smaller diameter than the first said cylindrical surface, the last said cylindrical surface being of a diameter at least equal to the diameter of the cylinder at any point between said surface and the rear end of the cylinder, a sleeve encircling the cylinder to form an exhaust chamber around the cylinder for the reception of exhaust fluid from the cylinder, said sleeve being split longitudinally to diffuse the exhaust fluid during its passage from the chamber to the atmosphere, said sleeve having one end of large diameter to engage the cylindrical surface on the hood and an end of smaller diameter for engaging the cylindrical surface on the cylinder, said ends of the sleeve being of smaller diameter than the surfaces which they engage to induce a tension in the sleeve sufficient to hold the sleeve in placed position, a shoulder on the cylinder acting as an abutment for the small end of the sleeve to prevent endwise movement of the sleeve in the forwardly direction, and a shoulder on the hood acting as an abutment for the large end of the sleeve to prevent endwise movement of the sleeve in the rearwardly direction.

In testimony whereof I have signed this specification.

FRED M. SLATER.
